W. H. RICHARDS.
WATER METER,
APPLICATION FILED AUG. 20, 1915.

1,186,610.

Patented June 13, 1916.

UNITED STATES PATENT OFFICE.

WALTER H. RICHARDS, OF NEW LONDON, CONNECTICUT.

WATER-METER.

1,186,610.

Specification of Letters Patent. Patented June 13, 1916.

Application filed August 20, 1915. Serial No. 46,434.

To all whom it may concern:

Be it known that I, WALTER H. RICHARDS, a citizen of the United States of America, residing at New London, Connecticut, have 5 invented a new and useful Water-Meter, of which the following is a specification.

This invention relates particularly to the rocking or nutatory disk type of meter, and the general objects of the invention are to 10 simplify and improve meters of this class.

Special objects of the invention are to increase the capacity of the meter, to reduce and simplify the parts, to reduce the wear on the several parts and to provide simple 15 and effective means for accurately adjusting the meter to correctly register the flow.

Other objects are to protect the meter against injury by freezing, and to provide readily accessible means for screening the 20 flow through the meter.

In the accomplishment of these objects I employ a disk and ball mounted to oscillate in a measuring chamber, and operate the registering or counting mechanism by 25 means carried by the peripheral portion of the disk. Said means is usually in the form of a pin projecting from the rim of the disk and working in a slot in the measuring chamber housing. This projecting pin or 30 actuator may be provided with an anti-friction roller, and it serves as it rocks back and forth in its guide slot to operate suitable gearing driving the counting mechanism. This construction leaves the ball 35 mounting at the center of the disk free of any parts projecting through the measuring chamber and permits of the disk being oscillated through a much greater angle than in the ordinary meter, thus, very materially increasing the capacity of the meter 40 without adding to its bulk or size. The driving gear may take the form of dogs or tumblers pivoted at the ends of the guide slot and extending thereinto so as to be 45 engaged by the actuator upon the disk, said dogs being geared together so that the actuation of one will position the other for engagement by the actuator.

Another feature of the invention is the 50 disposition of the meter casing and disk in a substantially vertical plane, and the locating of the inlet and outlet in the bottom of the meter, below the disk. This provides a very compact structure.

55 The frost protective device which I employ, is preferably in the form of a rela-

tively soft metal plug detachably screwed into the inlet throat of the meter.

The inflowing stream of liquid is preferably strained by a screen located in the inlet side of the meter, and to make this screen readily accessible for cleaning and renewal, that part of the casing in which this screen is located is preferably divided so that the casing can be separated on this line to fully 60 expose the screen. In the preferred construction the screen is located in the inlet and the inlet is cut at an angle sufficient to provide the necessary screening area.

The adjustment of the meter for correct 70 registration is obtained in accordance with my preferred construction, by the regulation of flow through a by-pass between the entrance and exit passages of the meter. Specifically this by-pass consists of a series 75 of ports in the partition between the intake and outlet side of the meter which may be opened up or closed by an adjustable gate, the increasing or decreasing of flow through this by-pass having a corresponding effect 80 in decreasing or increasing the rate of registration of the meter.

Various other features and details of construction will appear as the specification 85 proceeds.

In the accompanying drawing I have 90 illustrated a practical and preferred embodiment of my invention, but will have it understood that changes and modifications may be made without departing from the true scope of the invention.

Figure 1, is a vertical sectional view 95 through a meter embodying the several features of the invention, said view being taken substantially on the plane of the line 1—1 of Fig. 2. Fig. 2 is a vertical sectional view taken on a plane at right angles to that of Fig. 1. Fig. 3 is a horizontal sectional view taken substantially on the plane of the line 3—3 of Fig. 1. Fig. 4, is a sectional view 100 taken substantially on the plane of the line 4—4 of Fig. 2 showing the device for adjusting the registration of the meter.

In the illustration, the disk, designated 7, is shown provided with a ball 8 at its center which constitutes a pivot on which the disk rocks or oscillates in the measuring chamber 9. This measuring chamber is formed by an inner casing having dished or conical side walls 10 and 11, and a curved 105 annular wall 12 connecting the conical side walls. The conical side walls are provided

at their central portions with opposed bearings 13 and 14 for the pivot ball 8.

The inner or measuring chamber casing is supported within an outer casing 15. An 8 inlet 16 and an outlet 17 are provided in the base of this outer casing below the measuring chamber, said inlet and outlet being shown disposed in substantial alinement with each other, but separated by a partition 10 18. The partition 19 in the inner casing forms a continuation of the partition 18, separating the inlet side from the outlet side of the measuring chamber. On opposite 15 sides of this partition the measuring chamber is provided with openings 20 and 21 in communication with the inlet 16 and outlet 17 respectively. The disk is slotted at 22 so that it can oscillate over the partition 19.

The counting or registering mechanism 20 may be of any suitable construction and is represented in the present instance by the pointer carried by the upright spindle 25 which forms the main arbor or shaft of such mechanism and to which other pointers may 25 be geared as indicated in Fig. 1 at 23. This shaft has a bearing at 26 on the top of the inner casing, suitable packing being provided at 27, where said shaft passes down through the partition 28 which defines the 30 counting mechanism chamber 29. The actuator for the counting mechanism is in the form of a pin or projection 30 on the upper edge of the disk working in an arcuate slot 31 in the inner case and provided with a 35 friction reducing roller 32. The actuator 30 may be formed integral with the disk, or be a separate part attached thereto. In the illustration it is shown as a screw rod extended clear in through the disk into the 40 pivot ball at the center thereof. This makes a secure connection, and by distributing the strain through the disk and the pivot ball relieves the peripheral portion of the disk of any undue strain.

45 The complete oscillation of the disk is assured and the disk held against the walls of the measuring chamber by a pin or projection 33 on the ball which may be provided with an anti-friction roller 34 and which as 50 the disk oscillates, rides over the conical side wall 11 and thereby maintains the disk in its tilted position in engagement with the side walls at two diametrically opposite points, said guide roller passing through a slot in the partition 19, as indicated at 34' in Fig. 1.

The oscillating movement of the actuator in its segmental slot is communicated as a driving force to the counting mechanism in any suitable way, the means for this purpose 55 illustrated being in the form of two dogs or tumblers 35 and 36 mounted on spindles 37 and 38, and provided with oppositely extending fingers 39 and 40 arranged to project into the slot 31 into the path of the actuator, said spindles 37 and 38 carrying bevel

pinions 41 and 42 on their upper ends meshing with a beveled gear 43 on the arbor 25 of the counting mechanism. The inner casing is shown provided with diagonally opposite angularly extending housings 44 and 45 70 at the opposite ends of the slot in which the tumblers are mounted, openings 46 being provided in the inside walls of said housings for the fingers of the tumblers to work through. The tumblers are disposed at 75 right angles to each other as indicated in Fig. 3, so that when the finger of one tumbler is projecting into the actuator slot 31, the fingers of the other tumbler will lie parallel to said slot. Consequently, the engagement of the actuator with the active or projecting one of the tumblers, imparts a quarter turn to that tumbler and through the beveled gearing described turns the other tumbler a quarter revolution and into position 80 to be engaged by the actuator upon its return stroke. Upon each complete oscillation of the disk therefore the bevel pinions will be given a half turn, a proportionate movement being thereby imparted to the bevel gear and hence to the counting mechanism.

The construction disclosed permits of the disk swinging through a relatively wide angle, thereby giving increased capacity 95 without increasing the size of the meter. The placing of the inlet and outlet below the measuring chamber also conserves space and makes the meter more compact and inexpensive.

The inner casing may be split in two parts, as indicated at 47 to facilitate inspecting and assemblage and similarly the outer casing may be divided on the line 48 to permit ready access to the inner casing and 100 gearing.

A screen 50 is provided for straining the inflowing current of liquid. This screen is preferably located in the inlet 16 and the inlet is divided on an angle as indicated at 110 51 to provide the necessary screening area, the screen being held in place by being clamped between the two parts of the inlet. The two parts of the inlet may be secured together by bolts 52 or other suitable fastenings passed through the meeting flanges of said parts. After the inlet of the meter has been coupled to the service pipe, the removal of these bolts and the uncoupling of the outlet from its pipe connection, permits of the meter being lifted bodily off the inlet, thus allowing the bodily removal of the meter, exposing the screen and giving access to both inlet and outlet.

The parts are protected from freezing, 125 in the construction illustrated, by a frost plug 55, of relatively soft metal, screwed into the underside of the inlet and adapted to yield under the expansive pressure of freezing. When destroyed or distorted by 130

freezing this plug can be readily and cheaply replaced. This removable plug is preferably located as shown, adjacent to and beneath the inclined screen so that it can be utilized as a sediment trap, and be removed to free the inlet of the sediment collecting in the pocket beneath the screen.

The device for adjusting the registration (shown in detail in Fig. 4) may be placed 10 in any part of the meter where communication may be had between the inlet and outlet sides of the meter. In the illustration this is shown as located in the partition 18 (Figs. 2 and 4) and consists of a series of 15 ports 56 through the partition which may be opened or closed more or less by a gate 57, shown in the form of a plug screwed into the side of the casing and intercepting the port or ports. It will be clear that by adjusting this plug to open or close these leakage ports, more or less liquid will be bypassed around the measuring chamber and the meter will be thereby caused to decrease or increase its rate of registration. These 20 leakage ports are preferably made of a definite size and capacity so that the registration may be regulated by definite and certain steps. Thus for instance they might all be made of a size to vary the rate of 25 registration say one per cent., whereupon the opening up of one port would reduce the rate one per cent., the opening up of 30 two ports would reduce the rate of registration two per cent., etc., enabling accurate, 35 quick regulation of the meter. This provides a simple, convenient and practical means for "setting" the meter initially and for adjusting it subsequently to compensate for wear, sedimentation, etc., and dispenses 40 with the use of the "change-gears" heretofore employed for this purpose.

What I claim is:

1. In a disk type liquid meter, the combination with a casing having a measuring 45 chamber and a rocking disk mounted in said chamber and impelled by the flow of liquid therethrough, of counting mechanism and operating means upon the peripheral portion of said disk operatively connected with 50 said counting mechanism.

2. In a disk type liquid meter, the combination with a casing having a measuring chamber provided with a transversely extending segmental guide-way in one side 55 thereof, of a rocking disk mounted in said chamber, a projection on the edge of said disk working in said guide-way, counting mechanism, and connections for operating said counting mechanism including means 60 projecting into the segmental guide-way to be engaged and operated by the projection on the rocking disk.

3. In a disk type liquid meter, the combination with a casing having a measuring 65 chamber provided with a segmental guide-

way in one side thereof, of an oscillating disk mounted in said chamber, a projecting pin on the edge of said disk and a roller on said pin working in the segmental guide-way, counting mechanism, pivoted tumblers 70 having fingers adapted to extend into the segmental guide-way, and gearing between said tumblers and the counting mechanism.

4. In a disk type liquid meter, a casing having a measuring chamber provided with 75 a segmental guide-way in one side thereof, a pivot ball and disk oscillatably mounted in the measuring chamber, an actuating pin extending in through the body of the disk into the pivot ball at the center thereof, the projecting portion of said pin working in the guide-way aforesaid, counting mechanism and means operated by said projecting pin and operatively connected with said counting mechanism. 80

5. In a disk meter, the combination of a casing having a measuring chamber provided with a segmental guide-way in the upper side thereof, an oscillating disk in the measuring chamber, an actuator on the edge 90 of said disk working in said segmental guide-way, counting mechanism above the measuring chamber and operating means extending into the segmental guide-way into position to be engaged by said actuator and 95 operatively connected with the counting mechanism.

6. A liquid meter of the disk type comprising in combination with a casing having a measuring chamber provided with a guide-way in one side thereof, pivoted tumblers at the opposite ends of said guide-way provided with fingers adapted to project into said guide-way, pinions carried by said tumblers, a gear engaged by said pinions, registering mechanism operated by said gear, a disk oscillatably mounted in the measuring chamber, and an actuator on the edge of said disk traveling in said guide-way and arranged to engage the projecting fingers of 100 105 the tumblers.

7. A liquid meter comprising an outer casing provided with an inlet and an outlet in the bottom portion thereof, an inner casing within the outer casing above said inlet 110 and outlet and having an inlet and an outlet communicating with the inlet and outlet respectively of the outer casing, said inner casing having a guide-way in the top thereof, a disk oscillatably mounted in the inner casing, an actuator on the upper edge of said disk traveling in said guide way, registering mechanism and devices operatively engaged by said actuator and connected with said registering mechanism. 115 120 125

8. In a nutatory disk meter, the combination with a pivot ball and a disk carried thereby constituting together a nutatory element, of a meter chamber inclosing said nutatory element and comprising oppositely 130

- disposed side walls limiting the movement of the disk and provided with opposed sockets forming bearings for the pivot ball, registering mechanism outside said meter chamber, an actuator on the nutatory element inside the meter chamber defined by the side walls and bearing sockets aforesaid, whereby the space between said side walls may be increased to permit increased angle of movement of the disk without limitation by said actuator and driving connections between the actuator working within the meter chamber and the registering mechanism outside said chamber.
9. In a liquid meter, a casing having an inlet arranged for connection with a service pipe, the body portion of said casing being separable from said inlet on a line inclined with respect to the axis of the inlet and thereby providing at the plane of such separation a cross-sectional area greater than the cross-sectional area of the inlet and a screen clamped between the inclined meeting faces of the separable body portion of the casing and the inlet, the inclination of said line of separation being sufficient to provide the area necessary for screening substantially without increasing the diameter of the inlet.
10. In a liquid meter, a casing provided with an inlet, a screen disposed on an incline in said inlet and a plug detachably engaged in the inlet in the pocket provided beneath the incline of the screen.
11. In a meter of the character set forth, the combination with a disk and pivot ball at the center of the same, of a meter casing inclosing said disk and pivot ball, and means working within the meter chamber and engaged with the pivot ball of the disk for guiding and maintaining the nutatory action of the disk whereby said guiding means being disposed wholly within the meter chamber, the angle of said meter chamber may be increased without interference by said guiding means.
12. In a disk type liquid meter, the combination with a casing having a measuring chamber and a rocking disk mounted in said chamber and impelled by the flow of liquid therethrough, of counting mechanism, operating means upon the peripheral portion of said disk operatively connected with said counting mechanism and means for maintaining said disk in tilted position during the rocking movement thereof.
13. In a disk type liquid meter, the combination with a casing having a measuring chamber provided with oppositely disposed conical walls, a disk in said chamber, a guide at the center of said disk engaging one of said conical walls to thereby hold the disk in contact with the conical walls at diametrically opposite points, counting mechanism and operating means on the rim of said disk

operatively connected with said counting mechanism.

14. In a nutatory disk meter, the combination with a pivot ball and a disk carried thereby constituting together a nutatory element, of a meter chamber inclosing said nutatory element and comprising oppositely disposed side walls limiting the movement of the disk and provided with opposed sockets forming bearings for the pivot ball, registering mechanism outside said meter chamber, an actuator on the nutatory element inside the meter chamber defined by the side walls and bearing sockets aforesaid, whereby the space between said side walls may be increased to permit increased angle of movement of the disk without limitation by said actuator, driving connections between the actuator working within the meter chamber and the registering mechanism outside said chamber and means wholly within the meter chamber defined by said side walls and opposed bearing sockets for maintaining the disk in tilted position during nutation thereof.

15. In a device of the character set forth, a disk chamber having conical side walls provided with oppositely disposed seats devoid of enlarged openings for oscillating parts, a disk in said chamber and a pivot ball for said disk engaged in said seats and having no oscillating parts projecting through said seats, whereby the side walls of the disk chamber and disk may be designed to permit a vibration of the disk through an arc of ninety degrees or over.

16. A liquid meter provided with an inlet and with an outlet and with a partition between said inlet and outlet, said partition having a leakage port therein, a gate controlling said port and having an operating member extending out through the side of the meter casing, and liquid measuring mechanism interposed between the inlet and the outlet.

17. In a water meter a casing having a substantially horizontally disposed inlet in one side thereof and a horizontally disposed outlet in the opposite side thereof and substantially in alignment with said inlet and a substantially vertical partition in said casing between said inlet and outlet and forming a substantially vertical barrier separating the inlet from the outlet, said partition having a leakage port extending therethrough from the inlet to the outlet side thereof, a gate controlling said port and having an operating stem extending out through the side of the casing, a meter chamber in the casing above the inlet and outlet and having an opening in one side thereof in communication with the inlet and an opening in the opposite side thereof in communication with the outlet, a substantially vertical partition in said chamber in line

with and forming a continuation of the partition in the casing and thereby dividing the meter chamber into an inlet and an outlet side, a disk oscillatably mounted in the 5 meter chamber and having a nutatory movement imparted thereto by the flow of liquid from the inlet and through the chamber to the outlet and registering mechanism operated by said disk and governed as to its 10 rate of registration by the extent of leakage allowed through the leakage port in the partition which separates the inlet from the outlet.

18. In a device of the character set forth, 15 a disk chamber having conical side walls provided with oppositely disposed seats devoid of enlarged openings for oscillating parts, a disk in said chamber and a pivot ball for said disk engaged in said seats and 20 having no oscillating parts projecting through said seats, whereby the side walls of the disk chamber and disk may be designed to permit a vibration of the disk through an arc of ninety degrees or over, 25 and means engaged with the pivot ball of the disk and working wholly within the disk chamber defined by the conical side walls and seats for maintaining the disk in tilted position during nutation thereof.

30 19. In a device of the character set forth, the combination with a casing having a disk chamber and a rocking disk mounted in said chamber and impelled by the flow of liquid therethrough, mechanism to be operated 35 outside said disk chamber and operating means upon the peripheral portion of said

disk operatively connected with the mechanism to be operated.

20. In a device of the character set forth, a casing having a disk chamber, a rocking 40 disk mounted in said chamber and impelled by the flow of liquid therethrough, a pivot ball at the center of said disk, an actuating pin extending in through the body of the disk into the pivot ball at the center thereof 45 and means operated by the projecting portion of said actuating pin.

21. A liquid meter provided with an inlet and an outlet and a partition wall separating said outlet from said inlet, said partition wall having a plurality of transversely extending leakage ports therethrough of predetermined size and capacity providing a plurality of direct passages of 50 definite capacities between the inlet and outlet sides of the meter, said partition wall further having a longitudinal passage intercepting the ports extending therethrough, liquid measuring mechanism interposed between the inlet and outlet, registering mechanism operated by said measuring mechanism and a gate member movable longitudinally in the longitudinal passage to cut off or open up one or a number of said transverse ports to thereby vary by definite predetermined quantities the extent of leakage 55 past the measuring mechanism and thereby to regulate by certain definite steps the rate of registration produced by the measuring mechanism.

WALTER H. RICHARDS.
